DESIGN FOR A COMBINED WATCHCASE AND BROOCH OR SIMILAR ARTICLE

Emanuel Deutsch, New York, N. Y.

Application September 20, 1946, Serial No. 133,438

Term of patent 14 years

(Cl. D45—19)

To all whom it may concern:

Be it known that I, Emanuel Deutsch, a citizen of the United States of America, residing in New York city, county of New York, and State of New York, have invented a new, original, and ornamental Design for a Combined Watchcase and Brooch or Similar Article, of which the following is a specification, reference being had to the accompanying drawing, forming part thereof, wherein,

I claim:

The ornamental design for a combined watchcase and brooch or similar article, substantially as shown.

EMANUEL DEUTSCH.
